(57) **CLAIM**

I claim the ornamental design for a fall restraint bracket, as shown and described.

DESCRIPTION

FIG. 1 is a front view of the fall restraint bracket;
FIG. 2 is a top view of the fall restraint bracket;
FIG. 3 is a bottom view of the fall restraint bracket;
FIG. 4 is a left-side view of the fall restraint bracket;
FIG. 5 is a right-side view of the fall restraint bracket; and,
FIG. 6 is a perspective view of the fall restraint bracket, looking generally downward and from the left-side.
The broken lines shown in the drawings show unclaimed subject matter and form no part of the claimed design.
